PROCESS FOR THE MULTIPHASE ALKYLATION OF ISOPARAFFINS

Filed Jan. 30, 1939

UNITED STATES PATENT OFFICE

2,342,364

PROCESS FOR THE MULTIPHASE ALKYLATION OF ISOPARAFFINS

Farrand D. Parker, Los Angeles, Calif., assignor to Union Oil Company of California, Los Angeles, Calif., a corporation of California

Application January 30, 1939, Serial No. 253,503

9 Claims. (Cl. 260—683.4)

This invention relates to the treatment of hydrocarbon oils and refers more particularly to the production of gasolines of a superior value by synthetic reactions applied to the lighter and less valuable portions of crude petroleum oils and similar hydrocarbon mixtures. In a more specific sense, the invention has reference to a process which may be employed to supplement known crude oil treating processes to increase the obtainable yield of high anti-knock fractions suitable for use as fuel in internal combustion engines.

The comparatively recent adoption of high compression ratios in automobile and aviation engines to increase their thermodynamic efficiency placed a demand on the petroleum refining and similar industries to furnish hydrocarbon motor fuels of high anti-knock or slow burning characteristics. In a partial attempt to satisfy this requirement the petroleum industry has resorted to the use of cracking operations in which higher boiling hydrocarbons are subjected to elevated temperatures to produce motor fuels. However, these cracking operations are, at least, partially unsatisfactory. Thus, among other objections, the gasolines derived from such treatments of petroleum crude oils or their fractions do not possess the desired high knock ratings and are not sufficiently susceptible to substances of the type of tetraethyl lead. In other words, the addition of such a lead compound, within the permissible range, does not result in a motor fuel having sufficiently high anti-knock characteristics. Furthermore, all of the cracking processes produce more or less large amounts of normally gaseous hydrocarbons of varying compositions which, if not utilized, represent wasted natural resources. These normally gaseous hydrocarbons contain considerable proportions of olefins, particularly propylene and butylene. In connection with the operation of most modern refineries there are several sources of such olefin-containing normally gaseous hydrocarbon fractions. One of these is the gaseous fraction which is recovered during the release of pressure on the petroleum oils being subjected to cracking. These gases usually contain relatively large percentages of methane, but also contain other petroleum hydrocarbons including olefins ranging from ethylene into the normally liquid olefins which have been carried out by the gases. Generally, these fractions are subjected to absorption to recover most if not all of the normally liquid fractions. The remaining gases contain varying proportions of olefins of the type of propylene and butylene, as well as some hydrocarbons of the paraffinic type such as isobutane. Another source of the gaseous fractions is the overhead or reflux fraction obtained from the stabilization of the so-called pressure distillates.

These fractions contain very little and sometimes no methane, and generally predominate in olefins of the type of propylene and butylene. Obviously, the composition of the gases varies considerably depending upon the stock subjected to cracking, as well as on the processes employed.

It has recently been proposed to produce synthetic fuels by combining isoparaffinic or aromatic hydrocarbons with olefins. This reaction involves the contacting of these isoparaffins or aromatics and olefins in the presence of a suitable catalyst to produce a chemical combining of these hydrocarbons. The resulting product may be called a "product of alkylation," and may be generally described as consisting of saturated or cyclic hydrocarbon molecules with hydrocarbon chains or branches attached thereto. The above nomenclature was employed to distinguish this branched chain molecule from a "polymer" which is a product resulting from the interaction of two or more olefinic molecules. As an example of an alkylation reaction and the resulting product, reference may be made to the chemical combining of propylene or butylene with isobutane to produce, respectively, seven or eight carbon atom branched chain saturated hydrocarbon molecules. The optimum operating conditions for the alkylation of the various isoparaffinic hydrocarbons depend on the particular isoparaffin employed. For this purpose it has been generally considered advisable to produce a narrow cut or fraction predominating in a given isoparaffin. Furthermore, since normal paraffins do not react with olefins unless subjected to decomposing temperatures and pressures, it is advisable to fractionate the paraffinic hydrocarbons so as to isolate the particular isoparaffin even from its corresponding normal paraffinic hydrocarbon. Obviously, such procedure necessitates the use of special equipment for the narrow fractionation of the paraffinic hydrocarbons, thus greatly increasing the initial and operating costs of an alkylation plant.

As previously stated, products of alkylation are formed by the catalytic interaction of isoparaffins and olefins. Generally, this alkylation is conducted in a liquid phase, the liquefied isoparaffins such as isobutane or isopentane being first intimately commingled with the liquefied olefin containing fraction before the mixture is brought in contact with the alkylating catalyst such as sulfuric acid, a mixture of sulfuric and phosphoric acids or a metal halide catalyst such as aluminum chloride. Since the olefins are relatively highly reactive and tend to form polymers in preference to their alkylation of the isoparaffins, it is desirable, if not essential, to maintain an excess of the isoparaffinic hydrocarbon fraction. Although the isoparaffinic hydrocarbon employed for the production of high anti-knock

motor fuels may be obtained from other sources, these isoparaffins, and particularly isobutane, isopentane and isohexane, are mainly derived from the stabilization of gasolines extracted from natural gases. Some of these isoparaffinic fractions, being employed as reflux for such natural gasoline stabilization, are in a liquefied state and predominate in normal and isobutanes, although containing some propane. The isopentane and isohexane fractions may be recovered from the fractionation of natural gasoline. On the other hand, the olefinic fractions obtained as a by-product from cracking operations are often in a gaseous state so that if the alkylation reaction is to be realized in a liquid state, these olefin-containing gases must be liquefied, thus further adding to the cost of operations.

It is therefore the main object of the present invention to avoid the above difficulties and to provide a novel process for obtaining increased yields of high anti-knock motor fuel fractions by means of new and novel cooperation of the steps to be described. A further object of this invention is to obtain a motor fuel fraction having a high anti-knock value by processing a mixture of normally gaseous olefin-containing hydrocarbons derived from petroleum oil conversion or cracking processes, and liquefied saturated normally gaseous hydrocarbon fractions containing isoparaffinic fractions without the necessity of providing separate and special equipment for the narrow fractionations of these isoparaffinic hydrocarbon fractions. A further object of the invention is to provide an alkylation process for the production of high anti-knock motor fuel fractions in which process the separate fractionation of the isoparaffin-containing fraction is eliminated. A still further object is to produce a liquid motor fuel fraction having high anti-detonating characteristics, said process being economical and adapted to utilize a fluctuating supply of gaseous hydrocarbons of varying compositions.

It has been discovered that the above and other objects may be attained by providing a process in which the isoparaffinic fraction such as the isobutane, isopentane or isohexane fraction, is commingled, while in a liquefied state, with a gaseous mixture containing the olefins, and in which the mixed phase thus produced is contacted with the alkylating catalyst to cause the formation of products of alkylation by a chemical interaction between the liquid isoparaffins and the gaseous olefins. In the alternative, the liquefied isoparaffinic fraction may be commingled with the catalyst, and the mixture then thoroughly commingled with the gaseous olefins or olefin-containing gases. Although it was stated that the olefins are introduced in a gaseous state, a portion of these gaseous olefins are dissolved in the liquid isoparaffins, so that the hydrocarbons, strictly speaking, comprise a mixture which is in equilibrium and which comprises a mixture of both liquid and gaseous hydrocarbons.

It has also been discovered that a considerable saving in initial and operating expenses may be realized by eliminating special fractionating structures for the recovery of the substantially pure isoparaffinic fraction (such as isobutane) from the gaseous and/or liquefied hydrocarbons containing the same, and by fractionally treating these isoparaffin-containing gases together with the crude products of alkylation recovered from the treatment of isoparaffins with olefin. It is to be noted that the crude liquid fraction produced as a result of the interaction of an isoparaffinic

fraction (such as a hydrocarbon fraction predominating in isobutane) and of an olefin-containing hydrocarbon fraction, comprises a heterogeneous liquid mixture which, besides the true products of alkylation, also contains a fairly large percentage of the isoparaffinic hydrocarbon being alkylated, together with smaller quantities of other gaseous hydrocarbons which have been entrained or dissolved in the liquid product. In

view of this heterogeneous character of the crude product, the separation and recovery of the desired hydrocarbon fractions boiling within the gasoline boiling range and having the desired high anti-detonating characteristics necessitates a fractionation of the crude reaction product. According to the present invention, this same fractionation is utilized for the treatment of the isoparaffin-containing hydrocarbon fraction to recover therefrom the specific isoparaffin (such as isobutane) in a substantially pure state, this isoparaffinic fraction being recovered as a liquid and utilized as the feed or starting material for the formation of additional quantities of products of alkylation.

It has also been found that the unreacted gases leaving the alkylation reaction zone carry with them a considerable proportion of liquid products of alkylation as well as unreacted isoparaffins, such as isobutane, and that these reaction products may be recovered from the unreacted gases by washing or otherwise contacting these gases with the liquid products of reaction and particularly with a relatively heavy fraction thereof. Furthermore, one of the heavy fractions of the alkylation reaction products, and especially the fraction boiling above the gasoline boiling range, may be efficiently used as the heating medium for the reboilers which provide heat for the various fractionating towers, thus furnishing the heat source for the fractionation of the crude alkylation reaction product.

The drawing attached hereto, and which forms a part of the specification, represents a diagrammatic elevational view of a suitable apparatus for carrying out the present process. The olefin-containing normally gaseous hydrocarbon fraction is charged into the system through conduit 10. This may be the overhead gaseous fraction obtained from the stabilization of pressure distillate obtained during the cracking operations. This fraction contains relatively large quantities of olefins. Thus, the propylene-butylene content of this gaseous fraction usually exceeds 20%, and in most cases is above 30 or 35%. If it is desirable to also utilize the lean gases resulting from the absorption treatment of the gaseous fractions produced during the releasing of pressure on the cracked product, such gases may be introduced into the system through line 12. This gaseous fraction, although containing rather large quantities of methane and ethane, also contains appreciable quantities of olefins of the type of propylene and butylenes which are suitable for use in the process to be described herein. Thus, these lean gases contain as much as 10 to 15% of propylene and butylenes. Either or both of these olefin-containing gases are first subjected to a desulfurization operation for the removal of hydrogen sulfide therein. Although this hydrogen sulfide content of the gases is relatively small, being in the neighborhood of 0.25%, it has been found that the removal of this sulfide is beneficial and results in better yields and greater economy. To effect the removal of the hydrogen sulfide the olefin-containing gases are conveyed into a vessel

13 wherein the gases are brought in contact with an aqueous solution of an alkaline compound having an affinity for hydrogen sulfide. As an example, vessel 13 may be filled with an aqueous solution of sodium carbonate. The desulfurized hydrocarbons then leave vessel 13 through line 14 while the foul sodium carbonate solution containing the absorbed sulfur compound is withdrawn through line 15 and conveyed into the top of a regenerating tank 16 in which it is brought in contact with an upward draft of air introduced through line 17. The rejuvenated sodium carbonate solution is then withdrawn from the bottom of tank 16 through line 19 and is returned either continuously or intermittently back into the vessel 13 for further desulfurization of hydrocarbon gases. The air containing the hydrogen sulfide is withdrawn from the upper part of the regenerating tank 16 through pipe or vent 21.

As previously described, the alkylation of isoparaffins of the type of isobutane, isopentane and isohexane is best realized in the presence of a relatively strong sulfuric acid, for example, sulfuric acid having approximately a 98% H_2SO_4 content. To remove any water which may be present in the olefin-containing gases, the gaseous hydrocarbon fraction is conveyed through pipe 14 into a drier 23 which may contain any known drying material such as sodium sulfate. Although only one drying tank is shown in the drawing, it is obvious that a plurality of such tanks may be placed in parallel so that any one of such tanks may be isolated for the purpose of regenerating the sodium sulfate without the necessity of completely stopping the operations of the whole system. In the alternative the used dessicant may be removed and the driers recharged with a fresh drying agent. The dry olefin-containing gases are then conveyed through line 24 into a mixer 26 wherein they are commingled with a liquefied hydrocarbon fraction comprising crude products of alkylation and unreacted isoparaffins, such as isobutane, said isoparaffin containing hydrocarbon fraction being conveyed to the mixer through line 27. The isoparaffin-olefin mixture passes through line 28 and is contacted at 29 with the alkylating catalyst, such as strong sulfuric acid, which is introduced through line 30. For purpose of intimate commingling, the mixture then passes through a mixer or agitator 31 and is then conveyed through line 32 into a separator 33. In this tank, the sulfuric acid and the products resulting from the alkylation reaction settle to the bottom, are withdrawn through line 35, and conveyed into a settler 36. The sulfuric acid settles to the bottom of this settler 36 and is withdrawn through line 31. This acid may be recycled by conveying it through line 38 into line 30, leading the catalyst to the line 29 wherein said acid catalyst is continuously commingled with fresh quantities of hydrocarbons to be alkylated. If desired, the waste acid which is incapable of or uneconomical for alkylation of further quantities of isoparaffins and olefins may be withdrawn through line 38 while fresh acid or the like may be introduced into the system through line 40.

The supernatant hydrocarbon layer in settler 36 is withdrawn through line 43. A portion of this hydrocarbon fraction is separated for purposes of dilution and recirculation as this will be described in full hereinbelow. The balance of crude reaction products is commingled at 44 with a neutralizing agent, such as sodium hydroxide, introduced through line 45. This neutralization

is for the purpose of removing any traces of acid which may find their way into the hydrocarbon fraction being withdrawn through line 43. The mixture of hydrocarbons and neutralizing agent is then conveyed into settler 47, the sodium hydroxide depositing to the bottom of said settler and being recycled through line 45 for neutralization and washing of further quantities of the alkylate fraction, while the neutralized synthetic hydrocarbon fraction is withdrawn from settler 47 through line 48. Obviously, when necessary the neutralized alkali may be withdrawn and fresh sodium hydroxide introduced into the system.

The separator 33 may also comprise a flash chamber in which case line 32 is equipped with a pressure reducing valve 34. The alkylation reaction, as previously stated, may be realized at both atmospheric and superatmospheric pressures, and, in fact, somewhat elevated pressures may be advantageous both for the purpose of allowing the separation of the unreacted gaseous hydrocarbons in separator 33, and because such higher pressures permit the use of relatively higher temperatures while maintaining the isoparaffin, such as isobutane, in a liquid state. Obviously, when operating with a pressure reducing valve 34, it is essential to provide a pump for the recycling of the products of alkylation, as described more fully hereinbelow.

The unreacted gaseous hydrocarbons are withdrawn from separator 33 through line 50. Since a portion of the reaction products is entrained in the unreacted gases, these gases are conveyed into an absorber 51 wherein they are brought in countercurrent contact with an absorbing medium which, in the instant case, is a heavy fraction of the reaction products, this absorbing liquid or medium having been withdrawn from one of the fractionating towers to be described hereinbelow. This absorbing medium, after having been cooled to an optimum temperature in cooler 52 is introduced into absorber 51 through line 53. The recovered reaction product fraction, together with the absorbing medium, is withdrawn from the bottom of the absorber 51 through line 54, while the unreacted gases are withdrawn out of the system through pipe or vent 55 at the upper end of absorber 51. The mixture of reaction products conveyed through lines 48 and 54, after passing through surge tank 56 and a heat interchanger 57, is conveyed through line 58 into the first of a series of fractionating columns. However, prior to said introduction into said fractionating system the crude products of alkylation are first commingled with an isoparaffin-containing fraction introduced through line 59. As previously stated, this isoparaffin containing fraction may be a hydrocarbon mixture containing both normal and isobutanes and derived either as a side cut or fraction or as a reflux fraction in the stabilization of natural gasoline.

The fractionation of the isobutane-containing hydrocarbon and of the products resulting from the alkylation reaction is realized, according to the invention, in a plurality of fractionating columns. As shown in the drawing, the mixture passing through line 58 first enters the uppermost chamber of a multistage fractionator 62 from the bottom of which the heavier hydrocarbon fraction flows successively through two stages of the next fractionator 63. The heaviest fraction leaving the bottom of the last stage of the second fractionator 63 is partially employed as a heating medium for the fractionation of the mix-

ture consisting of the products of reaction and of the isoparaffins introduced into the system through line 59. It is obviously understood that the fractionation may be conducted either in a single multi-stage system having five or more stages, or may be realized in a number of single stage fractionators.

The hydrocarbon mixture entering the uppermost stage 65 is subjected to fractionation to cause the evaporation of propane and lighter gaseous hydrocarbons which leave through line 66. To cause this evaporation the hydrocarbons are heated to an optimum temperature and maintained under a necessary or optimum pressure. A portion of the overhead fraction withdrawn through line 66 is cooled at 61 and returned as reflux through line 68 back into the upper portion of stage 65. The bottom fraction is withdrawn through line 69 and passed through a heater or reboiler 70 wherein a part of the withdrawn material is vaporized and returned through line 71 back into stage 65 to provide the necessary heat for the evaporation of the propane and the lighter gaseous hydrocarbons. The heat for the reboiler 70 is provided from a source described below. The hydrocarbons withdrawn from stage 65 and remaining in a liquid state after the passage through reboiler 70 are continuously conveyed through line 72 into the next lower stage 74 wherein optimum temperature and pressure conditions are maintained so as to cause fractionation and to produce an overhead fraction predominating or substantially consisting of isobutane. The overhead gaseous fraction is withdrawn from this stage through line 75, condensed in cooler 76, and a portion returned through line 77 as a refluxing medium. The remaining isobutane fraction is conveyed through line 78 for use as the isoparaffinic hydrocarbon fraction to be alkylated. This isobutane fraction is first dehydrated in 79 as by means of sodium sulfate or like dessicating medium, and is then conveyed through line 80, and chiller 81 to line 27 leading to mixer 26 in which the isobutane is commingled with the olefin-containing gases. As previously stated, a portion of the crude alkylation reaction products leaving acid settler 36 via lines 43 and 82 is commingled with the isobutane fraction in line 80 for purposes of dilution and to prevent polymerization of the olefins.

The hydrocarbon mixture leaving the bottom of stage 74 through line 84 is further heated in reboiler 85 and the vaporized portion returned through 86 for purposes of providing the necessary heat to the fractionating stage 74. The remaining hydrocarbon mixture is then conveyed through line 87 into the lowermost stage 88 of fractionator 62 wherein the temperature and pressure are maintained so as to cause the evaporation of the normal butane fraction. This normal butane is withdrawn from the top of stage 88 through line 89 and either all or a portion thereof may be cooled in 90 to provide reflux which is returned through 91, the remaining normal butane being withdrawn from the system through 92. The liquid fraction leaving the bottom of fractionator 62 through line 93 is conveyed to reboiler 94 and, as in the previous cases, the vaporized portion of this heated fraction is returned through line 95 while the remaining material is conveyed through line 96 to the upper stage 98 of the second fractionator 63. The vapors evolved in this stage are withdrawn through line 99, condensed in cooler 100, and a portion returned as reflux through 101. This fraction

comprises a synthetic light gasoline fraction having a relatively high knock rating and suitable for use either alone or as a blending material in aviation engines. This fraction is withdrawn from the system through line 102. The bottom fraction leaving stage 98 through line 103 is split into two streams, one of which is conveyed through line 104 into the final fractionation stage 105. The remaining material leaving stage 98 is conveyed through line 106 and is employed as the absorbing medium in absorber 51. For this purpose this fraction is first conveyed through a heat interchanger 57 wherein it is cooled by the crude alkylation reaction products which are conveyed from surge tank 56 through line 58 into the first fractionating stage. The absorbing medium thus cooled is then conveyed through line 107 to cooler 52 and is then fed through line 53 into absorber 51.

The fractionator 105 causes the separation or fractionation of the alkylate fraction into three fractions, the lightest leaving through line 109 from the upper end of stage 105, and cooled and liquefied in 110. A portion of this fraction is employed for refluxing, and is returned through line 111. The balance of this fraction is withdrawn from the system through line 112, and comprises a light synthetic motor fuel fraction having excellent anti-knock characteristics and also suitable for use in aviation engines. The middle fraction is withdrawn through line 113, condensed in 114, and withdrawn from the system through line 115. This synthetic gasoline fraction, although having a higher end point, also possesses good anti-knock characteristics. A portion of the residual fraction withdrawn from the bottom of stage 105 through line 117 is employed for providing heat to the fractionating system. For this purpose, it is conveyed through line 118 to a heater 119. This heated hydrocarbon fraction is then conveyed through 120 to each of the reboilers 70, 85 and 94, the heating medium being conveyed to said reboiler through lines 121, 122 and 123, respectively. From these reboilers the heating medium is returned through lines 124, 125 and 126, and is conveyed through line 127 back to line 118 leading to the heater 119. A part of the heated hydrocarbons leaving heater 119 (through line 120) is conveyed through line 116 into the lower portion of stage 105 to provide the necessary fractionating heat. The excess heavy products of alkylation are withdrawn from the system through line 128.

Although the above description was made in connection with the alkylation of isoparaffins with olefins in the presence of strong sulphuric acid it is obvious that the process is not limited to the use of any particular catalyst, and that other catalysts which promote alkylation of isoparaffins with olefins may be employed. Thus, the catalyst may consist of a mixture of sulphuric and phosphoric acids, or may comprise or include chlorosulfonic acid and certain complexes of aluminum chloride or boron trifluoride. Also, the catalyst may consist of the above acids in combination with certain metallic salts such as phosphates, sulfates, chlorides, nitrates and acetates of metals of the type of cadmium, zinc, silver, mercury, copper and barium, these salts acting as activators to promote alkylation in preference to the polymerization of olefins. It is to be understood that the invention is not limited to the use of 98% sulfuric acid, since other strengths within the general range of 94% to 100% are suitable.

Also, although the invention is described in connection with a single preferred embodiment, it is obvious that a number of modifications, alterations and arrangements may be made without departing from the scope of the invention. For example, instead of employing both of the olefin-containing gases derived from the stabilization of pressure distillate and the gases obtained from the reduction of pressure in the cracking stills, it is possible to use either olefin gas, or any fraction thereof, or any other olefinic gaseous fraction, especially if it is rich in the desirable propylenes and butylenes. Also the heating of reboilers 70, 85 and 94 may be realized by employing hydrocarbon fractions other than the heavy reaction products removed from the bottom of the last stage 105. Furthermore, other heating media, such as steam, may be employed for this purpose. Also the absorption of the alkylate fractions carried out through the line 50 may be realized by employing any other absorbing medium besides the synthetic hydrocarbon fractions withdrawn through line 103 from the bottom of stage 88. Still further, in carrying out the invention, the conditions of operation chosen with respect to temperature, proportion of reacting constituents, choice of catalysts, as well as the strength of the acid, if such is employed as the catalyst, may be varied within a relatively large range to suit the individual case. Therefore, the above disclosure is merely illustrative of the preferred embodiments of the invention, and is not to be taken as limiting, since many variations thereof may be made within the scope of the following claims.

I claim:

1. A process for producing synthetic gasoline having high anti-detonating characteristics and substantially free from products of polymerization which comprises dissolving a normally gaseous olefin-containing fraction in a liquefied isoparaffin hydrocarbon having less than seven carbon atoms per molecule, contacting the liquefied hydrocarbon mixture in a reaction zone with strong sulphuric acid thereby producing a reaction mixture containing alkylated hydrocarbons and unreacted hydrocarbons, separating the acid catalyst from the said reaction mixture, removing the unreacted gaseous hydrocarbons from the reaction mixture, commingling an isoparaffin containing fraction with said reaction mixture from which the unreacted gaseous hydrocarbons have been removed, passing the said commingled hydrocarbon mixture through a fractionating zone thereby producing a fraction containing said synthetic gasoline and a fraction containing isoparaffins having less than seven carbon atoms per molecule and returning the latter fraction together with dissolved normally gaseous olefins to said reaction zone.

2. A continuous process for the alkylation of isoparaffinic hydrocarbons having less than seven carbon atoms per molecule with normally gaseous olefins to produce branched chain saturated hydrocarbons boiling within the gasoline range and having high anti-detonating characteristics, which comprises continuously commingling gaseous olefin-containing hydrocarbons with a substantially pure isoparaffinic hydrocarbon fraction maintained in a liquid state and with products of alkylation, contacting said mixture with strong sulfuric acid, thereby causing the interaction between the isoparaffins and the olefins to form products of alkylation, separating the unreacted

70 gases from the liquid phase, causing said liquid phase to separate into an acid phase and a hydrocarbon phase comprising the liquid unreacted isoparaffins and the products of the alkylation reaction, separately removing said phases, recycling a portion of the hydrocarbon phase through the alkylation reaction zone wherein said hydrocarbon phase is commingled with new quantities of isoparaffins and olefins to be alkylated, commingling the remaining hydrocarbon phase with isoparaffin-containing hydrocarbons, conveying said mixture through a fractionating zone to recover separately therefrom the desired branched chain hydrocarbon fraction boiling 15 within the gasoline range and a liquefied substantially pure isoparaffinic hydrocarbon fraction, and returning said last mentioned hydrocarbon fraction as the feed stock for the production of new quantities of branched chain hydrocarbons.

20 3. In a process according to claim 2 wherein the fractionation further produces a fraction boiling above the gasoline range and wherein said fraction is heated and returned into the fractionation zone to cause the fractionation of 25 fresh mixtures of products of reaction and of the crude isoparaffin-containing hydrocarbons.

25 4. In a process according to claim 2 wherein the unreacted gases withdrawn from the acid-hydrocarbon mixture are scrubbed with a portion 30 of the products of reaction to recover any entrained products of reaction.

30 5. In a process according to claim 2 wherein the acid phase, separated from the unreacted isoparaffins and the products of reaction, is recycled and commingled with fresh quantities of isoparaffins and olefins to produce their alkylation.

35 6. In a process according to claim 2 wherein the olefin-containing gases, prior to their commingling with their products of reaction and the isoparaffinic fraction, are desulfurized to remove 40 from said olefins the sulfur contained therein.

40 7. In a continuous process for the production 45 of branched chain hydrocarbons by the interaction of isoparaffinic hydrocarbons with normally gaseous olefins in the presence of a sulfuric acid catalyst, the steps of continuously commingling olefins with isoparaffins and products 50 of alkylation reaction, maintaining said mixture at superatmospheric pressure, contacting said hydrocarbons with sulfuric acid thereby causing the interaction between the isoparaffins and olefins to produce products of reaction, reducing 55 said pressure thereby separating the unreacted gaseous hydrocarbons from the liquid phase, causing the liquid phase to stratify into an acid phase and a hydrocarbon phase containing the liquid unreacted isoparaffins and the products of 60 reaction, and recycling a portion of said hydrocarbon phase for commingling with additional quantities of isoparaffins and olefins continuously introduced into the reaction zone.

65 8. In a process according to claim 7 wherein the separated acid phase is recycled for the catalytic alkylation of fresh quantities of isoparaffins and olefins.

70 9. In a process according to claim 7 wherein the gaseous fraction separated from the liquid phase is contacted with a fraction of the products of reaction to recover from said gaseous fraction any unreacted liquid products of reaction.

FARRAND D. PARKER.
